UNITED STATES PATENT OFFICE.

CHARLES ALGERNON PARSONS AND ALFRED QUINTIN CARNEGIE, OF NEWCASTLE-UPON-TYNE, AND STANLEY SMITH COOK, OF WALLSEND, ENGLAND; SAID CARNEGIE AND COOK ASSIGNEES TO SAID PARSONS.

CONSTRUCTION OF TURBINE AND LIKE ROTORS.

1,221,087.

Specification of Letters Patent

Patented Apr. 3, 1917.

Application filed October 9, 1913. Serial No. 794,353.

To all whom it may concern:

Be it known that we, CHARLES ALGERNON PARSONS, K. C. B., a subject of the King of Great Britain and Ireland, and residing at Heaton Works, Newcastle-upon-Tyne, in the county of Northumberland, England, ALFRED QUINTIN CARNEGIE, a subject of the King of Great Britain and Ireland, and residing at Heaton Works, Newcastle-upon-Tyne, in the county of Northumberland, England, and STANLEY SMITH COOK, a subject of the King of Great Britain and Ireland, and residing at Turbinia Works, Wallsend-on-Tyne, in the county of Northumberland, England, have invented a certain new and useful Improved Construction of Turbine and like Rotors, of which the following is a specification.

This invention relates to the construction of rotors for turbines and the like.

As at present constructed such rotors are generally made from a weldless steel tube or are machined out of a steel ingot, processes which are extremely costly, especially in the case of stepped rotors.

The object of the present invention is to provide a method of constructing rotors by which the rotor shall have great strength and rigidity and be produced at a smaller cost than has hitherto been possible.

The invention consists in a turbine or like rotor in which each of a plurality of short members suitably attached to one another or to the rotor shaft has a surface forming part of the total cylindrical surface of the rotor.

The invention further consists in a rotor constructed of a plurality of short members capable of formation by such ordinary processes as rolling, flanging or welding, and having means permitting of ready attachment to one another or to the shaft on which they are mounted.

The invention also consists in the improved construction of turbine and like rotors hereinafter indicated.

Referring to the accompanying drawings:

Figure 1 is a longitudinal section through a stepped rotor embodying one modification of the present invention and illustrates one form of attachment to the shaft.

Fig. 2 shows an alternative construction in which intermediate disks are omitted,

and also shows an alternative method of mounting upon the shaft.

Fig. 3 shows an alternative method of shaft attachment.

In carrying the invention into effect according to one construction, and as illustrated in Fig. 1, the short members, *a*, having a surface, *b*, forming part of the total cylindrical surface of the rotor are tubular; and have inwardly projecting circumferential flanges, *c*. Such members are preferably made by bending sheet metal of channel section into ring formation so that the flanges project inwardly and extend circumferentially. The ring is then completed by welding the ends of the sheet together by the oxy-acetylene or other known process, after which the ring is accurately machined, the flange faces being either plain or recessed to form spigots.

The short members or rings are then bolted or riveted together, as shown at *d*, to form a long tube with inwardly projecting ribs, the members being preferably arranged so that the welded joints of adjacent members do not come into line with one another, by which means increased strength of the structure as a whole is obtained independently of the strength of the welded joints.

Generally there is inserted between the adjacent rings or between pairs or groups of rings a plane disk *e*, having a central opening which is usually reinforced for instance by an angle ring, *g*, and may be mounted upon a hub fitting tightly on the rotor shaft *h*, or screwed to an enlarged part of the shaft, as at *h*. It is not essential, however, that all the disks rest upon the rotor shaft as clearance *f*, may in some cases be provided. Certain of the disks may conveniently be secured to the shaft by screwed rings *l*, holding them against shoulders.

The intervening disks *e*, are preferably of strength sufficient to support the entire circumferential portion of the drum independently of its circumferential strength so that, for example, in the case of a faulty weld of any one ring the structure will still be strong enough to withstand all stresses to which it is subjected.

Although a construction of rotor has been described in which the shaft is carried right

through the drum composed of short members with or without disks, the flanges of the short members are sometimes of sufficient thickness and rigidity that when the members are bolted or riveted together with or without the intervening disks, the whole tube thus formed has a rigidity approximating that of a uniform tube, but in regard to circular form, a rigidity superior to that of any uniform tube.

This construction is illustrated in Fig. 2 in which a plurality of channel ring members α , of the same diameter are bolted or riveted together. Where a change of diameter occurs a cast or forged reducing member 2 may be employed having flanges for the purpose of bolting it to the flanges of the members, α . At the high pressure end of the rotor, a special channel ring member 3 of cast steel is provided having a boss 4 bored to receive the shaft, k , and connected to the ring by webs, 5. A further flanged ring member 6 having one flange turned outward is provided to carry packing rings. The other end of the rotor is provided with a steel casting 7 carrying a boss 4 to receive the shaft k . The member 7 fits within the last flanged member of the rotor. To the side of the member 7 another member 6 for carrying packing means is provided.

Distance pieces, j , of any suitable shape may be inserted between the disks, e , resting upon the rotor shaft, k , see Fig. 3, and may be riveted or otherwise attached to the disk against which they abut, or if desired, the hub, g , reinforcing each disk may be so designed as to avoid the necessity for providing distance pieces between the disks.

When the disks are rigidly attached to a central shaft it is sometimes preferable to make some or all of the disks of such a thickness that their flexibility provides for a difference between the longitudinal expansion of the shaft and that of the outer portion of the drum. Also when necessary, suitable holes, n , may be made in the disks for the purpose of equalizing pressure or enabling the interior of the rotor to be readily accessible. Holes may also be provided in the disks and flanges for the escape of water.

Such a construction of rotor, it will be seen, is of great advantage when the rotor is of the stepped type comprising portions of different diameter, since it enables such a rotor to be constructed without difficulty and at a cost only slightly in excess of that of a rotor of constant diameter.

In a rotor constructed in accordance with the present invention the separate members may be attached to the shaft in any con-

venient manner, either along the whole or part of the length of the assembled rotor, and may, for instance, be held together between nuts and abutments on the shaft or by means of bolts passing through the members, and securely connecting the same with suitable abutments on the shaft.

In applying the present invention to the construction of a stepped rotor, it will be seen that it is only necessary to vary the diameter of the members forming part of the rotor cylindrical surface in order to obtain the required number of steps. The construction of the rotor is thus rendered less expensive than hitherto, while the construction is one having great strength and rigidity.

The improved construction may, moreover, be applied to rotors for turbines of any type, whether of the impulse, reaction or combined impulse reaction types, and is also applicable to the construction of wheels such as are used for the gearing in land or marine turbine installations.

Having now described our invention, what we claim as new and desire to secure by Letters Patent is:—

1. A rotor comprising channelled members bent into ring form, each with its ends welded, said ring shaped members thereby having annular flanges and means for uniting a plurality of said members together to form a group, substantially as described. 90

2. A rotor comprising in combination a plurality of channel section elements united in a group, a further plurality of channel section elements of less diameter than the first mentioned elements united in a second group, elements having inwardly turned flanges connecting said groups of elements, and spiders connected to the free ends of said groups of elements. 100

3. A rotor, comprising in combination a group comprising a plurality of channel section elements, means connecting said elements, a further group of channel section elements of less diameter than said first mentioned elements, means connecting said further group of channel section elements, elements having inwardly turned flanges between said groups of elements, and means connecting said inwardly turned flanges to said groups of elements. 110

In testimony whereof, we affix our signatures in presence of two witnesses.

CHARLES ALGERNON PARSONS.
ALFRED QUINTIN CARNEGIE.
STANLEY SMITH COOK.
